UNITED STATES PATENT OFFICE.

HERBERT D. LE SUER, OF SEYMORE, IOWA.

MITER-BOX.

1,240,228.

Specification of Letters Patent. Patented Sept. 18, 1917.

Application filed September 14, 1916. Serial No. 120,095.

To all whom it may concern:

Be it known that I, HERBERT D. LE SUER, a citizen of the United States, residing at Seymour, in the county of Wayne, State of Iowa, have invented certain new and useful Improvements in Miter-Boxes; and I do hereby declare the following to be a full, clear, and exact description of the invention, such as will enable others skilled in the art 10 to which it appertains to make and use the same.

This invention belongs to the class of miter boxes, and has particular reference to adjustable miter boxes in which the saw and 15 the work can be set at relatively different angles.

The primary object of the invention is to generally improve the construction of adjustable miter boxes, increasing the range of 20 operation of the saw, and to permit the use of the box on work not ordinarily cut in miter boxes, namely, curved work and other pieces having other than straight sides.

A further object is to provide a miter box 25 which is capable of being folded into compact relation when not in use. In connection with this object attention is called to the fact that the device is not rendered inoperative in its folded condition, but may be 30 used within certain limits for making cuts, thus making the device of particular advantage when cutting space or supporting space is limited.

As a further object of my invention it is 35 contemplated to provide a peculiar form of saw hanger by means of which the saw is supported in contact with the work.

With the above objects in view, and such other objects as may hereinafter appear, my 40 invention will now be fully set forth and described, reference being had to the accompanying drawings.

In the drawings:—

Figure 1 is a front elevation of the device,

Fig. 2 is a rear elevation,

Fig. 3 is a side view,

Fig. 4 is a plan view showing the device in folded position,

Fig. 5 is a section on line 5—5 of Fig. 3,

Fig. 6 is a section on line 6—6 of Fig. 3,

Fig. 7 is a section on line 7—7 of Fig. 3, and

Fig. 8 is an elevation of one of the folding sections.

Referring more particularly to the drawings, 1 denotes a standard or pintle upon

which are mounted the two box sections 2 and 3. Each one of the sections 2 and 3 consists of a side 4 substantially forming a quadrant and having at its upper end an overturned bearing 5 and at its lower end the feet 6. Extending from the side 4 above the feet 6 is a base 7 which is also quadrant shaped having the center of the quadrant located in a bearing 8 which is journaled upon the lower end of the standard or pintle 1. Thus, the sections 2 and 3 are supported upon the standard 1 by means of the bearings 5 and 8, and when assembled, the base of the section 2 overlies the base of the section 3 so that the two sections may be folded upon one another about the standard 1 until the walls or sides 4 stand at right angles to one another. Furthermore, the walls or sides 4 are adapted to be swung into longitudinal alignment so that their outer faces lie in the same vertical plane.

Mounted upon the outer face of each one of the sides or walls 4 is a shelf or table 9, one end of each shelf being pivoted to the corresponding wall 4 at a point adjacent the standard 1, a bracket 10 secured below the table 9 providing a suitable pivoting point. When mounted upon the walls 4, the upper surfaces of the tables 9 are in longitudinal alignment. The outer ends of the tables 9 carry the brackets 11, in whose vertical sides are mounted the set screws 12 which are operative in arcuate slots 13 of quadrant length formed in the walls 4. The sides or walls 4 are graduated to mark degrees and pitches as indicated in Fig. 1 in order to provide for the arcuate adjustment of the tables 9 to various inclinations. In order to provide a suitable background for the tables 9, the sides 4 are formed with the extension webs 14 of sufficient length to overlie the tables 9 practically to the outer extremities thereof.

Also pivoted upon the standard or pintle 1, and slidably operative over the base 7 of the section 2 is a guide bar and support 15. The guide bar 15 consists of a flattened rod which constitutes a base for a pair of guide rods 16 whose lower ends are threaded into the bar 15 and lie thence in parallel relation to one another and to the standard 1 to a suitable height above the base 7. The upper ends of rods are coupled by means of a transverse coupling or bracket 17. Fixed upon the rods 16 is a pair of tubular brackets 18 which have the inwardly extending wings 19 extending therefrom in parallel

relation. Between the wings 19 and the bars 16 is pivotally supported the guide 20 which is secured to the wings 19 by means of the screws 21 upon which the guide 20 rocks. The guide 20 consists of a pair of spaced parallel plates which are joined along their upper edges by means of a tubular member 22 through which the back of a miter saw may operate, the saw blade lying 10 between the spaced plates of the guide. The forward end of the guide 20 extends through the slot 23 formed vertically in the pindle or standard 1 of such length as to permit a suitable vertical play of the guide 15 20 as it rocks upon the screws 21.

The guide bar 15 has its free end extended beyond the marginal or peripheral edge of the base plate 7, and is provided with the depending manually operative 20 clamp 24, the latter having a foot 25 which may be clamped against the marginal or peripheral edge of the base plate 7. The bar 15 is also recessed over the portion of the base plate 7 and carries the pointer 26 25 which is adapted to register with the graduations 27 formed on the base plates in order to permit the arcuate setting of the saw guide. Also mounted below the guide rods 16 below the tables 9 are the adjustable collars 28 which may be set in order to limit the depth of a cut, by forming stops for the guide 18.

In operation, the device is ordinarily set up by placing the walls 4 of the sections 2 35 and 3 in alinement, so that the tables 9 appear in the same horizontal plane in front of the sections 2 and 3, and the saw guide and the rods 16 together with the guide bar 15 extend rearwardly from the standard 1 and the walls 4. Thus, in this invention, the cutting tables are located upon one side of the device which is wholly clear of all other operative parts, so that there is no limit to the width of the wood which may 40 45 be cut other than what may be defined by the length of the saw used. After the walls 4 have been set in alinement, if there is no angular cut, other than an ordinary miter cut to be made, the proper adjustment of 50 the saw is made by swinging the bar 15 over the bases 7 until the saw stands at a proper angle when the clamp 24 is set to hold the parts in the adjusted relation, when the material supported upon the tables 9 may be 55 cut. If the cut should have an angle other than the ordinary miter cut, as for the purpose of cutting a molding for a roof having a half pitch and an angle of 45 degrees where it abuts the foot of a rafter the miter 60 box is folded to the position of Fig. 4, then the table 9 is set to half pitch or 45 degrees and the guide bar 15 is also set to 45 degrees, when the cut may be made with positive accuracy. When the two sections of 65 the box are in closed position, the two tables

9 are at right angles to one another, and when set to their horizontal position, that is, parallel with the bottom of the miter box, any ordinary miter can also be cut, but the range of the tables is considerably 70 widened in that more acute angles can be cut, the limit being set only by the length of the saw. Furthermore, when opened so that the tables lie beyond a straight line, the device is admirably suited for making 75 radius cuts upon wheel fellys and other kinds of circular work, the relative positions of the tables being adapted to the curvature of the fellys. Aside from the advantages arising from the increased operativeness of the device, it should be noted that it can be materially shortened by folding the sections 2 and 3 one upon the other so that it can be readily packed, this being an advantage of considerable value when 80 it is considered that the ordinary adjustable miter box is not capable of being readily stored and transported in a carpenter's tool chest. It should also be noted that the present structure is capable of being produced 85 almost entirely of sheet steel or pressed steel, the several elements which make up the body of the structure being capable of being stamped and shaped into the proper form. 90

What I claim is:—

1. A miter box, comprising in combination, a standard, a pair of sections mounted upon said standard, each of said sections consisting of a front wall and a base, and 100 the bases being mounted on the front walls so that one base will slide upon the other when the walls are brought into right-angular relation, tables carried by said walls and adapted to be brought into horizontal alinement when the sections are extended, a saw guide also mounted in said standard and means to adjust the saw guide relative to the section in open or closed position. 105

2. A miter box, comprising in combination, a standard, a pair of sections mounted upon said standard to swing therearound, each of said sections consisting of a quadrant shaped base and a front wall, the bases being associated to slide one upon the other 110 when the walls are carried into right-angular relation, a saw guide operative over the bases, means for adjusting the saw guide relative to the base, and tables mounted on the front walls and adjusted thereon to the 115 various angles of the saw guide.

3. A miter box, comprising in combination, a standard, a pair of sections mounted upon said standard to rotate thereabout, each of said sections having a front wall, 120 said walls being adapted to be brought into alinement, a table carried by each of said walls, means for adjusting said tables to various vertical angles on said front wall, and a saw guide mounted on said standard. 130

4. A miter box, comprising in combination, a standard, a pair of sections mounted upon said standard to rotate thereabout, each of said sections having a front wall, said walls being adapted to be brought into alinement, a table carried by each of said walls, means for adjusting said tables to various vertical angles on said front walls, and a saw guide mounted on said standard, said saw guide consisting of a bar having one end pivotally secured to the standard, a

pair of guide rods vertically mounted upon the guide bar and guide plates pivoted between said guide rods and extending through said standards.

15

In testimony whereof, I affix my signature, in the presence of two witnesses.
